UNITED STATES PATENT OFFICE.

CHARLES B. RICHARDS, OF CLEVELAND, OHIO, ASSIGNOR TO THE CLEVELAND PNEUMATIC TOOL COMPANY, OF CLEVELAND, OHIO, A CORPORATION OF OHIO.

IMPACT-TOOL.

No. 910,860.

Specification of Letters Patent.

Patented Jan. 26, 1909.

Application filed December 20, 1906. Serial No. 348,709.

To all whom it may concern:

Be it known that I, CHARLES B. RICHARDS, a citizen of the United States, resident of Cleveland, county of Cuyahoga, and State of Ohio, have invented certain new and useful Improvements in Impact-Tools, of which the following is a specification, the principle of the invention being herein explained and the best mode in which I have contemplated applying that principle, so as to distinguish it from other inventions.

The annexed drawings and the following description set forth in detail, one mechanical form embodying the invention; such detail construction being but one of various mechanical forms in which the principle of the invention may be used.

In said annexed drawings, Figure I represents an axial section of my improved impact tool taken on the line D—X in Fig. VII, and showing the parts in their positions at the beginning of the forward or downward stroke of the plunger; Fig. II, an axial section of the tool on the line K—G in Fig. VII, and showing the parts in their positions near the end of the forward or downward stroke of the plunger; Fig. III, an axial section on the line K—G in Fig. VII, and showing the parts in their positions at the extreme of the forward or downward stroke of the plunger; Fig. IV, an axial section on the line D—G in Fig. VII, and showing the parts in their positions at the beginning of the rearward or upward stroke of the plunger; Fig. V, an axial section on the line D—G in Fig. VII, and showing the parts in their positions near the rearward or upward stroke of the plunger; Fig. VI, a diagrammatic axial sectional view of the valve-block and valve; and Fig. VII, a rear or inner end view of the barrel.

My present invention relates to direct-acting fluid-pressure engines such as usually employed to impart the impact of their reciprocating piston to the shank of a working tool, such as a chisel, calking-tool, rivet-set or other similar tool, and the illustrated embodiment of the invention will here be referred to as a hammer; but it is evident that the reciprocating manifestation of energy created in the tool from fluid under pressure may be otherwise applied and translated by suitable attachment to the reciprocating piston.

The illustrated hammer has a tubular bar-

rel, 1, the interior axial bore of which forms the working-cylinder within which a piston, 2, reciprocates. The lower or forward end of the barrel has a tool-socket, 3, in which the shank of the working-tool, 4, fits. This tool is here illustrated as a rivet-set for upsetting and shaping the heads of rivets. A grasping-handle, 5, has its split socket, 6, screwed upon the upper or rear end of the barrel and clamped by means of a bolt, 7. An inlet-socket, 8, is provided for the attachment of a hose or other flexible connection to the source of motive fluid under pressure,—compressed air being the usual motive fluid and the term "live-air" being here generally used in referring to such fluid. The bottom of the handle-socket is formed with an annular inlet-chamber, 9, communicating with the inlet-socket by a channel, 10, controlled by a manually-operated throttle-valve, 11. A valve-easing is clamped between the upper or rear end of the barrel and the bottom of the handle-socket, and consists of an annular button or disk, 12, having an annular nose which fits into the upper or rear end of the working-cylinder, a cylindrical valve-block, 13, and a rear button or disk, 14. An annular exhaust-chamber, 15, is formed around the valve-easing, between the circumference of the latter and the sides of the socket, and the latter has exhaust-ports, 16, communicating with the surrounding atmosphere. The barrel of the hammer has a longitudinal distributing channel, 17, in its wall, which channel extends from an enlargement, 18, in the lower or forward end of the working-cylinder at the upper or rear end of the tool-shank, to the upper or rear end of the barrel. A so-called "kicker-channel" and port, 19, extends longitudinally through the wall of the barrel from a point about the middle of the working-cylinder of the same and a distance slightly in excess of the length of the piston from the upper end of the tool-shank, to the upper or rear end of the barrel. An exhaust-port and channel, 20, opens from the working-cylinder near the upper or rear end of the same and longitudinally through the wall of the barrel to the upper or rear end of the same.

Only one bore for each channel and port is illustrated in the drawings, although in actual practice, for the purpose of increasing the capacity of such channels and parts,

more than one bore may be and usually is employed.

The valve-block is formed with an axial bore or valve-chamber which has a large-diameter piston-chamber, 21, at its upper or rear end, which is closed by the rear button or disk 14. A channel, 22, extends through the lower button or disk, the side or wall of the valve-block and into the upper or rear 5 button or disk, where it connects with a radial passage, 23, in said button or disk, which opens into the upper or rear end of the piston-chamber. A permanent exhaust-passage, 24, also extends radially from the upper or 10 rear end of said piston-chamber and connects with the annular exhaust-chamber surrounding the valve-casing. A permanent exhaust-port, 25, extends from about the middle of the side of the piston-chamber 21, out to the 15 exhaust-chamber. Another permanent exhaust-port, 26, extends from the lower or forward end of this piston-chamber, out to the annular exhaust-chamber. An annular rib, 27, is formed at the lower or forward end 20 of the piston-chamber, separating said chamber from an annular exhaust-groove, 28, which is connected to the exhaust-channel and port 20 in the barrel by means of an angular exhaust-passage, 29, through the 25 side of the valve-block and through the lower or forward button or disk 12. An annular rib, 30, of greater internal diameter than the rib 27, separates this latter annular exhaust-groove from an annular exhaust-groove, 31, 30 immediately below or forward of the former groove, and said latter exhaust-groove communicates with the annular exhaust-chamber by means of a radial exhaust-port, 32, through the wall of the valve-block. An 35 annular distributing groove, 33, is formed below or forward of the lower exhaust-groove, and is separated from said groove by an annular rib, 34, of the same internal diameter as the rib 30. Said distributing groove 33 40 communicates by means of a passage, 35, through the wall of the valve-block and through the lower or forward button 12, with the distributing channel 17 in the barrel. An annular live-air groove, 36, is formed below or forward of said distributing groove 45 and is separated from the same by an annular rib, 37, of the same internal diameter as the two preceding ribs, and said live-air groove communicates with the annular inlet-chamber 50 9 in the handle-socket by means of a passage, 38, in the wall of the valve-block and through the upper or rear button 14. An annular rib, 39, is formed at the forward end 55 of this inlet-groove, and is of the same internal diameter as the three preceding ribs but of greater internal diameter than the internal diameter of the opening in the lower or forward button or disk. The valve-block has thus an axial valve-chamber consisting 60 of the piston-chamber 21 of larger diameter 65

and the lower or forward chamber of smaller diameter and formed by the four annular ribs and the annular grooves or ports formed between said ribs.

Two telescoping valve-bodies, 40 and 41, have play within the entire valve-chamber. The lower or forward valve-body is of a diameter which fits within the smaller diameter valve-chamber and has a reduced middle portion, 42, which forms a narrow lower or forward piston, 43, and an upper wide piston, 44. The narrow lower piston has play over the inlet-groove or port so as to close the same off from communication with the upper or rear end of the interior of the working-cylinder, when the valve-body is in its lower or forward position and connect the inlet-port with the distributing port and passage leading to the lower or forward end of the working-cylinder, and to close off said latter port and passage when the valve-body is in its raised or rear position and to uncover the opening for the inlet-port into the upper or rear end of the working-cylinder. The upper and wide piston 44 of the lower valve-body has milled openings, 45, in its upper edge, so that communication between the upper or rear exhaust-ports and passages from the working-cylinder to the exhaust-port 32 may be established when the valve-body is in its lower or forward position, while such communication is cut off when the valve-body is in its raised or rearward position. The lower or forward valve-body is formed with a cylindrical recess, 46, extending from its rear end and closed at the forward end, and said recess has small exhaust-ports, 47, through the wide piston of the valve-body. The upper or rear valve-body 41 has a piston, 48, which slides in the large-diameter piston-chamber 21, and a body-portion, 49, which fits and slides within the annular rib 27 so as to close the lower or forward end of said piston-chamber. A reduced neck, 50, projects from the lower or forward end of said body-portion, and has a piston, 51, which has a snug but sliding fit within the cylindrical recess 46 of the lower or forward valve-body. One or more auxiliary exhaust and relief ports, 52, are formed in the barrel from the interior of the working-cylinder out to the atmosphere, at a distance from the lower or forward end of the barrel so as to be uncovered by the plunger when the latter is on its upward or rearward stroke, but to be covered by the plunger when the latter arrives at the lower or forward end of its stroke and to remain so covered when the plunger reaches the shank of the working-tool and to be thereupon uncovered when the plunger forces the working-tool downward or forward as it delivers its blow upon the shank of said tool, as illustrated in Fig. III of the drawings.

In describing the operation of the hammer, 130

we will assume that the live-air inlet is suitably connected to a source of air or other fluid under pressure, that the throttle-valve is opened to admit air into the hammer, and that the several parts of said hammer are in the positions illustrated in Fig. I of the drawings. Under these conditions the air passes from the inlet and through the live-air passage 38 and live-air port in the valve-chamber to the upper or rear end of the working-cylinder, through the open lower or forward end of the valve-chamber, so as to force the plunger downward or forward to deliver its actuating blow upon the tool-shank. The air below or in front of the advancing plunger is exhausted through the auxiliary exhaust-port 52 and through the distributing port and channel 17—35, to the distributing port 33 in the valve-chamber, which port is connected to the exhaust-port 31—32 in said chamber by the reduced portion 42 of the lower valve-body. It will thus be seen that exhaust takes place from the lower portion of the working-cylinder during the entire downward or actuating stroke of the plunger. The exhaust-port 52 aids in rapidly exhausting air in front of the advancing plunger, but is not absolutely essential in this capacity to the working of the hammer when the distributing port and channel from the lower end of the working-cylinder has a sufficient capacity. While the above movement of the plunger is taking place, the two valve-bodies are in their uppermost positions,—the lower valve-body being held upward by the pressure of live-air against its lower piston-area, and the upper valve-body being held in its raised position by the air within the recess in the lower valve-body acting against the lower face of the piston within the same. When the plunger arrives at the lower portion of its down-stroke and strikes the shank of the tool, as illustrated in Fig. II, the plunger uncovers the "kicker-port" 19 and its passage, so as to allow live-air to pass upward through said port and passage to the upper end of the large-diameter piston-chamber of the valve-chamber, and to cause said air to act against the large-diameter piston of the upper valve-body and force the same downward, as shown in Fig. II. The small exhaust-ports in the side of the piston-chamber admit of this movement being unobstructed. The downward movement of the upper valve-body compresses the air within the recess in the lower valve-body. The downward movement of the upper valve-body causes the lower piston of said body to uncover the small ports 47 in the lower valve-body so as to permit the pressure in front of said lower valve-body to be reduced by its being able to exhaust through the rear exhaust-port and passage 20—29, through the milled openings 45 and past the neck 50 and through ports 47 to the exhaust. As the plunger strikes the shank of the working-tool and moves the latter downward in its socket, as shown in Fig. III, the exhaust or relief port 52 in the forward portion of the working-cylinder is uncovered by the plunger, so that the pressure in front of or below the lower valve-body will be very much reduced. This will admit of the lower valve-body being moved downward by the expansion of the air within its recess, so that the inlet of live-air in to the upper end of the working-cylinder is cut off and the live-air port is placed in communication with the distributing port which conveys air to the lower end of the working-cylinder, as shown in Fig. III. The air in the piston-chamber of the valve-block, above or behind the piston of the upper valve-body, in the meanwhile expands against the large area of the piston and again compresses the air within the recess of the lower valve-body by the small area of the lower piston, so as to occupy the position illustrated in Fig. IV. The rear exhaust-port and passage from the working-cylinder has now been connected to the exhaust in the valve-chamber, so that the air above or behind the plunger which is now forced upward by the live-air passing down through the long distributing passage, may freely exhaust. The expansion of the air in the recess of the lower valve-body forces the upper valve-body upward into its raised position, as shown in Fig. V, and the returning plunger cuts off the rear exhaust when it arrives towards the end of its up-stroke, as shown in said figure, thus trapping the remaining air between it and the lower face of the lower valve-body and compressing the same, so as to force the lower valve-body upward into the position shown in Fig. I, whereupon the above described operation will again be repeated. The small exhaust or relief ports 47 in the recess of the lower valve-body will serve to prevent excess accumulation of compressed air within the recess or the formation of a more or less vacuum within such recess, both of which conditions would interfere with the free telescopic action of the two valve-bodies. The exhaust-ports 25 and 26 in the piston-chamber of the valve-block permit of the large piston of the upper valve-body moving freely within the piston-chamber, and the permanent exhaust 24 in the upper end of this piston-chamber provides means for exhausting air admitted above or behind the piston in said chamber, so as to allow said piston to be moved upward or rearward.

Great speed and positive motion of the valve-mechanism and, consequently, of the plunger is obtained in this hammer by constructing the valve-mechanism with two valve-bodies fitted together so as to form an air-cushion between them, so that when posi-

tive pressure against one or the other of the pressure-areas of the two bodies is released, the expansion of the air-cushion will move such part to cause the entire two-part valve-
5 structure to occupy the required position. The lower or forward valve-body is the distributing valve, proper, and the upper or rear valve-body simply acts to compress the air-cushion for moving the distributing valve-
10 body downward or forward. The piston at the lower end of the upper or rear valve-body also performs a valvular function as shown in Fig. II, by establishing a relief below or in front of the lower valve-body to permit
15 of the same being moved downward or forward by the expansion of the compressed air-cushion in its recess. The completion of this relief to permit the lower valve-body to be shifted downward is accomplished by the uncovering of the port 52 when the descending plunger pushes the working-tool outward and thus uncovers said port.

As the valve-mechanism comprises two distinct and separately operating valve-bodies, I do not desire to claim a valve actuated in one direction by air compressed by the returning plunger and in the opposite direction by air under normal pressure admitted to the valve and controlled by the plunger.
25 I also do not desire to claim an auxiliary permanently-open exhaust port at the front end of the cylinder which is uncovered by the rear or upper end of the plunger when the latter reaches the shank of the working-
30 tool, but only such port when uncovered by the plunger after the latter has moved the tool-shank outward.

Other modes of applying the principle of my invention may be employed for the mode herein explained. Change may therefore be made as regards the mechanism thus disclosed, provided the principles of construction set forth respectively in the following claims are employed.

45 I therefore particularly point out and distinctly claim as my invention:—

1. In a fluid-pressure engine, a distributing valve having one pressure-area exposed to and acting against an inclosed permanent air-cushion and an opposed pressure-area, and ports and passages for admitting and exhausting motive-fluid to and from said latter pressure-area, whereby the valve is moved in one direction by motive-fluid to
50 compress the air-cushion and in the opposite direction by the expansion of such air-cushion when the motive-fluid pressure against the opposite pressure-area is released.

2. In a fluid-pressure engine, a distributing valve-mechanism comprising a valve-body formed with a cylindrical recess closed at one end and with an opposed pressure-area and a valve-body formed with a piston fitted to slide and cushion within the recess
65 and with an opposed pressure-area, and

ports and passages for admitting and exhausting motive-fluid to and from the pressure-area of the valve-bodies.

3. In a fluid-pressure engine, a distributing valve-mechanism composed of two valve-bodies having an interposed air-cushion between them and opposed pressure-areas, and ports and passages for admitting and exhausting motive-fluid to and from the pressure-areas of the valve-bodies. 75

4. In a fluid-pressure engine, the combination with a working-cylinder and a plunger reciprocable within the same, of a distributing valve-mechanism comprising two valve-bodies having an interposed air-cushion between them and opposed pressure-areas, and ports and passages controlled by the reciprocating plunger and conveying motive-fluid to and from said pressure-areas. 80

5. In a fluid pressure engine, the combination with a working-cylinder and a plunger reciprocable therein, of a distributing valve-mechanism composed of two bodies having an interposed air-cushion between them and one valve-body having a pressure-area exposed to intermittently applied normal motive-fluid pressure and the other valve-body having a pressure-area exposed to air compressed between it and the moving plunger. 85

6. In a fluid pressure engine, the combination with a working-cylinder and a plunger reciprocable therein, of a distributing valve-mechanism composed of two valve-bodies having an interposed air-cushion between them and having pressure-areas opposed to 100 said air-cushion, and passages controlled by the plunger to relieve the pressure upon such area and to thus allow the expansion of the air-cushion to move a valve-body. 95

7. In a fluid-pressure engine, the combination with a working-cylinder and a plunger reciprocable therein, of a distributing valve-mechanism comprising two valve-bodies having telescoping and cushioning fit in one another and one valve-body having a pressure-area exposed to normal motive-fluid pressure and the other valve-body having a pressure-area exposed to air compressed between it and the moving plunger. 105 110

8. In a fluid-pressure engine, the combination with a working-cylinder and ports and passages for the distribution of motive-fluid, and a plunger reciprocable within the cylinder, of a distributing valve-mechanism comprising valve-bodies having telescoping and cushioning fit in one another and having pressure-areas opposed to their cushioned areas and exposed to the action of motive-fluid through the ports and passages. 115 120

9. In a fluid-pressure engine, the combination with a working-cylinder and a plunger reciprocable therein and a working-tool having its shank fitted in the end of said cylinder,—the cylinder being formed with a relief port at a distance from such end to be un- 125 130

covered by the plunger when the latter strikes and moves outward the tool-shank, of a valve-chamber opening into the opposite end of the working-cylinder and formed with an 5 inlet-port at such open end, and a valve in said chamber movable over said inlet-port and having an air-cushion tending to force it across said port against the inlet-pressure.

10. In a fluid-pressure engine, the combination of a working-cylinder, a plunger reciprocable in such cylinder, a piston-chamber above or to the rear of the cylinder and formed with a permanent exhaust-port and with a port and passage opening in the working-cylinder to be uncovered by the upper 15 end of the plunger at the downward stroke of the same, a valve-chamber below said piston-chamber and of less diameter than the latter and opening directly into the upper end of the 20 working-cylinder and formed with an inlet-port in its lower end, a distributing port communicating with the lower end of the cylinder, an exhaust-port communicating with the atmosphere and a port communicating 25 with the working-cylinder near the upper end of the same, a valve-body having play in the valve-chamber and formed with pistons controlling the ports in the same and with a cylindrical recess closed at its forward 30 end, and a valve-body formed with a piston having play within the recess and with a large-diameter piston having play within the piston-chamber.

11. In a fluid-pressure engine, the combination of a working-cylinder having ports and passages 17, 19 and 20, a plunger reciprocable therein, a valve-casing formed with live-air port 36, distributing port 33, exhaust-port 31 and port 28 and with a piston-chamber 35 40 45 50 55 60 65 70 75 80 85 90 95 100 105 110 115 120 125 130 135 140 145 150 155 160 165 170 175 180 185 190 195 200 205 210 215 12. In a fluid-pressure engine, a distributing valve-mechanism for controlling the admission and exhaust of motive-fluid to and from the opposite ends of the working-cylinder and consisting of two valve-bodies, one of which bodies controls the distribution and is moved in one direction by air compressed by the plunger and the other of which bodies is moved in the opposite direction by normal-pressure motive-fluid, and each of which bodies actuates the other through an interposed air-cushion by compression and subsequent expansion of the latter.

13. In a fluid-pressure engine, a distributing valve-mechanism for controlling the admission and exhaust of motive-fluid to and from opposite ends of the working-cylinder and consisting of a valve-body having a large pressure-area connected to be exposed to normal-pressure motive-fluid admitted by the plunger and an opposed small pressure-area, and a valve-body having a closed recess in which the small pressure-area of the former body has play and an opposed pressure-area exposed to plunger-compressed air and of less area than the normal-pressure-area of the former body.

14. In a fluid-pressure engine, a distributing valve-mechanism for controlling the admission and exhaust of motive-fluid to and from the opposite ends of the working-cylinder and comprising two valve-bodies having longitudinally-sliding cushioned play in their relation to one another and having means for admitting plunger-controlled motive-fluid to their opposed pressure-areas and for alternately relieving such pressure against such areas.

In testimony that I claim the foregoing to be my invention I have hereunto set my hand this 7th day of December A. D. 1906.

CHARLES B. RICHARDS.
